UNITED STATES PATENT OFFICE.

ALBERT JAEGERS, OF SUFFERN, NEW YORK, ASSIGNOR TO THE SEGAR STUDIOS INC.
A CORPORATION OF NEW YORK.

DESIGN FOR A LIGHTING-FIXTURE BRACKET.

Application filed July 14, 1924. Serial No. 10,148. Term of patent 7 years.

To all whom it may concern:

Be it known that I, ALBERT JAEGERS, a citizen of the United States, and a resident of Suffern, county of Rockland, and State of New York, have invented a new, original, and ornamental Design for Lighting-Fixture Brackets, of which the following is a specification, reference being had to the accompanying drawing, forming a part hereof.

The drawing shows an elevational view of

the lighting fixture bracket, the part shown in full line outline being ornamented in the same manner as the part more fully illustrated.

I claim:

The ornamental design for a lighting fixture bracket substantially as shown and described.

ALBERT JAEGERS.
